(57) **CLAIM**

We claim the ornamental design for an inhalation device for the delivery and storage of powdered medicaments, as shown and described.

DESCRIPTION

FIG. 1 is a right side elevational view of an inhalation device for the delivery of powdered medicaments showing our new design;

FIG. 2 is a left side elevational view thereof;

FIG. 3 is a top plan view thereof;

FIG. 4 is a front elevational view thereof;

FIG. 5 is a rear elevational view thereof;

FIG. 6 is a bottom plan view thereof;

FIG. 7 is a rear elevational view of the inhalation device for the delivery and storage of powdered medicaments, with the spout and lid shown removed for ease of illustration;

FIG. 8 is a front elevational view thereof;

FIG. 9 is a right side elevational view thereof;

FIG. 10 is a left side elevational view thereof;

FIG. 11 is a top plan view thereof;

FIG. 12 is a bottom plan view thereof;

FIG. 13 is a front elevational view of the spout portion of the inhalation device for the delivery and storage of powdered medicaments, with the body and lid shown removed for ease of illustration;

FIG. 14 is a rear elevational view thereof;

FIG. 15 is a top plan view thereof;

FIG. 16 is a bottom plan view thereof;

FIG. 17 is a right and front perspective view thereof; and,

FIG. 18 is a left side and front perspective view thereof.
